United States Patent Office.

JAMES J. ESSEX, OF NEWPORT, RHODE ISLAND.

Letters Patent No. 96,095, dated October 26, 1869.

IMPROVED UTERINE SYRINGE.

The Schedule referred to in these Letters Patent and making part of the same.

To all whom it may concern:

Be it known that I, JAMES J. ESSEX, of Newport, in the county of Newport, and State of Rhode Island, have invented a new and improved Enema and Uterine Syringe; and I do hereby declare that the following is a full, clear, and exact description thereof, which will enable others skilled in the art to make and use the same, reference being had to the accompanying drawings, forming part of this specification.

My invention is an improvement on the syringe patented July 28, 1863, to C. A. Jozansi, No. 39,348, and is designed to obviate a serious difficulty incident to the operation of his device, as hereinafter explained.

In the drawings is represented a side view of my invention in use.

Similar letters of reference indicate corresponding parts.

A represents a valve-box, to one end of which an eduction-tube, B, is secured, an elastic bulb, C, being connected to the opposite end, and an elastic suction-pipe, D, connected to the side of it, as shown.

The bulb C is not connected directly to the valve-box, the former being provided with an elastic extension-tube, E.

The elastic tube E will admit of the eduction-tube B being inserted in the rectum or womb with facility, and, at the same time, admit of the elastic bulb C being operated by the hand with the greatest possible convenience, as will be clearly understood by referring to the drawing.

The ordinary syringes are attended with a great deal of inconvenience in their use, in consequence of an absence of flexibility between the eduction-tube and the bulb. This assertion applies to those syringes which are provided with a flexible suction-tube communicating at right angles, or nearly so, with a valve-box; for in these syringes, it will be understood that the suction-tube must extend downward into the ves-

sel containing the water or other fluid to be injected into the rectum or womb, and this position of the suction-tube, together with the position of the rectum or womb, renders it impossible to have the bulb without an elastic neck, brought into a convenient position to be operated.

The tube B is formed with an external bulb, a*, a short distance from its end, in order to limit the extent of the penetration of the tube into the mouth of the womb, and also to prevent the escape of the injection liquid therefrom.

I have found that a rigid curved tube, such as that shown in Jozansi's case, will not properly perform the function required, since the action of the bulb will move the discharge-pipe.

In my invention, the bulb has entirely independent motion, so that when the syringe is applied to an inflamed vagina, or other passage, the discharge-pipe will remain at rest, thus avoiding causing pain to the patient. The flexible tube also allows the operator to hold it or the bulb in any desired position, wholly irrespective of the discharge-tube, thus rendering the assistance of a second person unnecessary, in case the patient has the requisite strength and knowledge for properly applying the instrument.

In view of the above, I desire to claim nothing shown in the patent referred to.

Having thus described my invention,

What I claim as new, and desire to secure by Letters Patent, is—

An improved syringe, as specified, consisting of the bulb C, elastic neck E, body A, and rigid discharge-tube B, each of said parts being constructed as hereinbefore described.

JAMES J. ESSEX.
